UNITED STATES PATENT OFFICE.

JOHN W. DALY, OF CINCINNATI, OHIO.

GARMENT-PRESSING MACHINE.

1,257,194.

Specification of Letters Patent. Patented Feb. 19, 1918.

Application filed January 5, 1917. Serial No. 140,673.

To all whom it may concern:

Be it known that I, JOHN W. DALY, a citizen of the United States of America, and resident of Cincinnati, in the county of Hamilton and State of Ohio, have invented a new and useful Improvement in Garment-Pressing Machines, of which the following is a specification.

My improved garment pressing machine 10 is of the type having a movable presser head adapted to be pressed against a stationary presser head by means of a foot treadle. In pressing machines of this type the movable presser head is directly connected with the 15 foot treadle. In order to permit the movable head to be raised sufficiently from the stationary head it has been necessary to give the foot treadle too great a range of movement and thus lift it too high from the floor 20 for the operator to lift his foot without unnecessary exertion. This and also the effort necessary to lift the head by hand and simultaneously to place the connected treadle in position to receive the operator's foot for 25 another pressing operation, tires the operator.

To overcome these objections I have devised my improved pressing machine in which an object is to produce means for dis- 30 connecting the movable presser head from the treadle when it is desired to move the head by hand and for automatically connecting the head with the treadle to adapt the treadle to be operated by the operator's foot.

35 A further object is to provide means for locking the movable presser head in pressing engagement with the stationary head after pressing movement of the treadle, with releasing means capable of operation by the 40 operator's foot, for permitting return of the treadle to its normal position and operative disconnection thereof from the movable head.

These and other objects are attained in 45 the pressing machine described in the following specification and illustrated in the accompanying drawings; in which;

Figure 1 is a side elevation of my improved pressing machine, showing the parts 50 in their normal inoperative positions, certain parts being broken away and shown in section for convenience of illustration.

Fig. 2 is a side elevation of the machine shown in Fig. 1, but showing the parts in 55 their operative positions.

Fig. 3 is a sectional plan view taken on the line 3—3 of Fig. 1.

Fig. 4 is an enlarged sectional view taken on the lines 4—4 of Fig. 3.

Fig. 5 is a sectional view of the parts disclosed in Fig. 4, but in different positions.

My improved pressing machine embodies two features of novelty. The principal feature of novelty consists of the means for automatic disconnection and connection of 60 the treadle with relation to the movable head. The remaining feature of novelty consists of the means for locking the treadle and presser head in their operative positions and for releasing them therefrom.

The means for automatically connecting and disconnecting the treadle 6 with relation to the movable head 7, consists of plates 8 and 9 reciprocally mounted in ways 10 and 11 formed in tracks 12 and 13 located on 70 opposite sides of a link 14 connecting the treadle with the movable head, and mounted in an enlarged rear portion 15 of the treadle. The tracks 12 and 13 are inclined toward one another from their upper to their lower 75 edges. The plates 8 and 9 each consist of a lower portion 16 projecting through the bottom of enlargement 15 of the treadle 6 and having extensions 17 and 18 in which are formed slots 19 and 20 adapted to receive the 80 ends of rollers 21 and 22, these rollers being adapted to engage the inclined surfaces of the tracks 12 and 13 in order to be forced against the sides of the link 14 and into gripping engagement therewith. Beneath 85 the lower portions 16 of the plates 8 and 9 are the branches of a fork 23 formed on the rear end of a lever 24 pivotally mounted in lugs 25 extending from the lower edges of the side flanges of the treadle 6. The forward end of the lever 24 extends upwardly and through a slot 26 formed in the top or web portion of the treadle, this end being bent to form a finger 27 adapted to engage the top of slot 28 formed in the front of the 90 frame 29 of the pressing machine, when the treadle is in its normal position as disclosed in Fig. 1. In this position the plates 8 and 9 are lifted so that the rollers 21 and 22 are 95 released from gripping engagement with the link 14. In order to retain the treadle in its normal position, a spring 30 is provided, the spring being secured at its upper end to the frame and at its lower end to the treadle as disclosed in Figs. 1 and 2. When the treadle 100 105 110

is moved downwardly the end 27 of the lever 24 is released from engagement with the upper end of slot 28 and the weight of the rear end of the lever 24, together with that 5 of plates 8 and 9 and of rollers 21 and 22, causes the rollers to engage the inclined surfaces of the tracks 12 and 13 and to bring the rollers into engagement with the sides of the link 14 so as to grip the link 14 and 10 to prevent movement thereof with relation to the rear end or enlargement 15 of the treadle.

At the front end of the treadle 6, a pawl 31 is provided, the pawl extending through 15 a slot 32 formed in the web of the treadle, and pivotally mounted in lugs 33 extending from the side flanges of the treadle. Between its ends, the pawl is pivotally connected with one end of a trigger 34 which extends for 20 wardly to the enlarged front end 35 of the treadle, which is adapted to be engaged by the operator's foot. The forward end of the trigger 34 is provided with an upward extension 36 which passes through a slot 37 25 formed in the enlargement 35, so that the trigger may be engaged by the operator's foot. The trigger is connected with one end of a spring 38, the opposite end of which is connected with the treadle as disclosed in 30 Figs. 1 and 2, so that normally the tension of spring 38 will be to cause rearward movement of pawl 31 and trigger 34. The position of pawl 31 is such that when the upward extension 36 of trigger 34 is brought 35 beneath shoulder 39 formed in enlargement 35 of the treadle, the pawl will be caused to enter the slot or opening 28 just beneath its upper end, so that the treadle will be held in its lower or operative position as disclosed in Fig. 2. Means are provided for 40 releasing the trigger and pawl from their treadle-locking positions, consisting of a bell crank lever 40 pivotally mounted at a point 41 in the enlargement 35 of the treadle, and 45 having one end located back of and adapted to engage upward extension 36 of the trigger 34, the opposite end of the bell crank having an upwardly projecting end or pin 42 which extends through a slot 43 formed in enlargement 50 35 of the treadle and in position to be engaged by the operator's foot. By moving pin 42 toward the edge of enlargement 35, the end which engages the upward extension 36 of the trigger, will withdraw the trigger 55 from the position disclosed in Fig. 2 and bring it in alignment with slot 37 formed in extension 35. A leaf spring 44 or other suitable means, is provided for lifting the trigger and projecting upward extension 36 60 through the slot 37 to the position disclosed in Fig. 1, ready for reengagement thereof by the operator's foot. This action of withdrawing the trigger from the position disclosed in Fig. 2 to that disclosed in Fig. 1,

withdraws the connected pawl 31 from its locking position as disclosed in Fig. 2 to its releasing position as disclosed in Fig. 1, so that the treadle and movable head may again be moved to their normal or inoperative positions.

In operation;

The machine will be considered to have its parts in the positions disclosed in Fig. 1, the treadle 6 being lifted, the gripping rollers 21 and 22 released, trigger 34 in position to be released by the operator's foot, and the movable head raised as disclosed in full lines in Fig. 1. The operator first places the garment to be pressed on the lower pressing head 45 of the machine, then by hand draws down the movable pressing head 7 to the position disclosed in dotted lines in Fig. 1. This movement is facilitated by the counter balance weight 46 of link 14. Because of the disconnection of gripping rollers 21 and 22 from link 14, they occupying the positions disclosed in Fig. 4, link 14 will be permitted readily to pass through enlargement 15 of the treadle 6, until movable head 7 engages stationary head 45. With the heads in this position, the operator places his foot on upward extension 36 of trigger 34 and presses it downwardly until disengaged from shoulder 39 and simultaneously presses treadle 6 downwardly until forward end 27 of lever 24 is disengaged from the upper end of slot 28. At this time fork 23 of lever 24 drops and permits plates 8 and 9 to drop in their mounting ways 10 and 11 to bring rollers 21 and 22 into engagement with the inclined surfaces of tracks 12 and 13 and consequently to grip the opposite sides of link 14. Continued downward movement of treadle 6 thus brings the movable presser head into pressing engagement with stationary head 45 because of the gripping action of rollers 21 and 22 with link 14, and its downward movement is continued until pawl 31 passed beyond the upper end of slot 28 formed in standard 29 of the machine. Since the upward extension 35 of trigger 34 has been released by the operator's foot from shoulder 39, spring 38 causes rearward movement of trigger 34 and pawl 31 so that pawl 31 engages slot 28, as disclosed in Fig. 2. This locked position of the treadle permits of the operator maintaining the pressure necessary to press the garment between the upper and lower presser heads, until that portion of the garment has been thoroughly pressed. As soon as sufficient time has passed for the garment to be pressed, pin 42 of bell crank 40 is engaged by the side of the operator's foot and the trigger and its connected pawl are withdrawn from their treadle-locking positions. This releases the treadle and permits of its actuating spring 30 lifting it to its normal position and to such a point that the

forward end 27 of lever 24 engages the upper end of slot 28 in standard 29 and lifts plates 8 and 9, thereby releasing rollers 21 and 22 from engagement with tracks 12 and 13, as disclosed in Fig. 4. This releases link 14 and permits weight 46 to lift the upper or movable presser head 7 from its pressing position as disclosed in Fig. 2, to its inoperative position as disclosed in full lines in

10 Fig. 1.

With my improved construction it will be seen that the operator is enabled to secure a relatively great amount of movement of the movable presser head, which will enable him 15 to have sufficient access to the stationary presser head in the placing of garments thereon to be pressed. My improved construction also enables the operator to have access to the foot receiving portion of the 20 treadle without having to lift his foot through too great a distance and thereby tiring him before completion of the day's work.

A further advantage is attained by my improved construction in that the operator is 25 enabled to maintain the pressure necessary to properly press a garment between the two presser heads, without having to stand on the operating treadle in order to do so. 30 This relieves the operator from the necessity of having constantly to attend the machine and permits him to operate additional machines or attend to other duties which devolve upon him, such as preparing other 35 garments for the pressing operation and hanging up and folding garments which have previously been pressed.

Having thus described my invention, what I claim is:

- 40 1. A pressing machine comprising a stationary presser head, a movable presser head, a treadle, a bar for connecting the movable presser head and the treadle, and means adapted automatically to disconnect the 45 treadle from operative connection with the bar when the treadle is in its inoperative position, and to connect the treadle there with when moved from its inoperative position.
- 50 2. A pressing machine comprising a stationary pressing head, a movable presser head, a treadle, a bar for connecting the movable presser head and the treadle, the

bar having under certain conditions a sliding engagement with the treadle, the bar 55 being confined by a portion of the treadle so that one side of the bar remains a constant distance from an inclined surface provided upon the treadle adjacent the surface of the bar, a roller means for mounting said roller 60 between the surface of the bar and the inclined surface, the roller mounting means adapted to move the rollers into binding engagement with and between the bar surface and the inclined surface, and means for 65 moving the roller mounting means.

3. A pressing machine comprising a stationary presser head, a movable presser head, a treadle, a bar for connecting the movable presser head and the treadle, and 70 means adapted automatically to disconnect the treadle from operative connection with the bar when the treadle is in its inoperative position, and to connect the treadle therewith when moved from its inoperative position, said means comprising inclined walls formed on opposite sides of a hole located in the treadle on each side of the bar which passes through the hole, a plate located in the treadle on each of the remaining sides 80 of the bar and having slots formed therein, a roller mounted in the slots on each of the first mentioned sides of the bar and between it and its adjacent incline, and a lever pivotally mounted on the treadle and having 85 one end adapted to engage the plates and its opposite end adapted to engage the frame of the machine when the treadle is in its normal position, whereby the plates will be maintained in an elevated position to withdraw 90 the rollers from engagement with the first mentioned sides of the bar and the inclines, and whereby the lever will be disengaged from the frame when the treadle is moved to its operative position to permit the plates 95 to drop to bring the rollers into gripping position between the inclines and the first mentioned sides of the bar.

In testimony whereof, I have hereunto subscribed my name this 3rd day of January, 1917.

JOHN W. DALY.
